(57) **CLAIM**

The ornamental design for a robot, as shown and described.

DESCRIPTION

FIG. 1 is a rear, top perspective view of a robot;

FIG. 2 is a front, top perspective view thereof;

FIG. 3 is a plan view of one side thereof;

FIG. 4 is a plan view of the other side thereof;

FIG. 5 is a plan view of the front thereof;

FIG. 6 is a plan view of the rear thereof;

FIG. 7 is a rear, top perspective view of a second embodiment of a robot

FIG. 8 is a front, top perspective view thereof

FIG. 9 is a plan view of one side thereof

FIG. 10 is a plan view of the other side thereof

FIG. 11 is a plan view of the front thereof

FIG. 12 is a plan view of the rear thereof

FIG. 13 is a rear, top perspective view of a third embodiment of a robot

FIG. 14 is a front, top perspective view thereof

FIG. 15 is a plan view of one side thereof

FIG. 16 is a plan view of the other side thereof

FIG. 17 is a plan view of the front thereof

FIG. 18 is a plan view of the rear thereof

FIG. 19 is a rear, top perspective view of a fourth embodiment of a robot

FIG. 20 is a front, top perspective view thereof

FIG. 21 is a plan view of one side thereof

FIG. 22 is a plan view of the other side thereof

FIG. 23 is a plan view of the front thereof; and,

FIG. 24 is a plan view of the rear thereof.

The broken line in FIGS. 7-24 is for illustrative purposes only and forms no part of the claimed design.
